BOLT ACTION FIREARM

Frank F. Burton, Mount Carmel, Conn., assignor to Winchester Repeating Arms Company, New Haven, Conn., a corporation of Maryland

Application February 25, 1933, Serial No. 658,562

13 Claims. (Cl. 42—16)

This invention relates to an improvement in bolt-action firearms and relates in particular to means for locking the manual operating-member thereof against effective operating movement when the firing-pin is in other than its advanced or forward position. Such means is commonly referred to as an "action lock."

An object of the present invention is to provide a bolt-action firearm with simple, reliable and effective means for releasably locking the manual breech-bolt operating-member against effective operating movement when the firing-pin is in other than its advanced position.

A further object is to provide a bolt-action firearm having convenient and reliable locking means, as above referred to, and which may be produced at a relatively low cost for manufacture.

Other objects and advantages will appear to those skilled in the art from the following, taken in conjunction with the accompanying drawings and appended claims.

In the accompanying drawings:

Fig. 1 is a broken view in side elevation of one form which a bolt-action firearm embodying the present invention may assume;

Fig. 2 is a broken view, mainly in side elevation and partly in vertical section, of the receiver portion and immediately adjacent parts of such a firearm, the breech-bolt being shown in its closed position and the firing-pin and hammer being shown in the positions which they assume when a cartridge is fired;

Fig. 3 is a view corresponding to Fig. 2, showing the action-slide moved slightly rearwardly to take up the lost motion between the same and the breech-bolt, the breech-bolt being also shown by broken lines in its fully retired position;

Fig. 4 is a similar view, but showing the hammer as cocked, the breech-bolt closed, the firing-pin in its retired position, and the action-slide latch in its latching position;

Fig. 5 is a longitudinal sectional view taken on the line 5—5 of Fig. 4;

Fig. 6 is a perspective view of the breech-bolt detached, and showing the action-slide latch and firing-pin in place therein;

Fig. 7 is a broken perspective view of the rear end of the action-slide; and

Fig. 8 is a perspective view of the action-slide latch.

The particular firearm herein chosen as illustrative of the present invention includes a receiver 10 having attached to its rear end the usual butt-stock 11 and having projecting from

its forward end the usual barrel 12. Mounted directly below the barrel 12 and arranged parallel therewith is a tubular magazine 13 upon which is mounted, with capacity for reciprocating movement, an action-slide handle 14 having a rearwardly-projecting action-slide bar 15.

The rear end of the action-slide bar 15 above referred to rides in a longitudinal guide-groove 16 formed in the inner face of the left side-wall of the receiver 10 and opening inwardly into the hollow interior of the said receiver in the usual manner of firearms of the type illustrated. Adjacent its extreme rear end, the action-slide bar 15 is provided with an inwardly-projecting cylindrically-contoured bolt-operating lug 17 entering into an inclined cam-slot 18 formed in the left side of a breech-bolt 19 mounted in the upper portion of the receiver 10 with capacity for both longitudinal reciprocating and vertical rocking movement with respect thereto.

For convenience of description, the cam-slot 18 in the breech-bolt 19 may be said to have a lifting cam-surface 20 gradually merging into the top wall 21 of the cam-slot 18. Complementing the lifting cam-surface 20 is a depressing cam-surface 22 joined to the cam-surface 20 before referred to, by a substantially-semicircular reach 23 and merging into the top wall 21 by a similarly-curved reach 24. It will be noted by reference to Fig. 6 in particular that the lifting cam-surface 20 is more steeply inclined than is the depressing cam-surface 22, with the result that the forward upper portion of the cam-slot 18 provides room for limited free play or idle movement of the bolt-operating lug 17 therein. The lug 17 and the slot 18 thus serve to provide for the lost-motion connection of the action-slide bar 15 to the breech-bolt 19.

Above the cam-slot 18 the left side of the breech-bolt 19 is formed with a recess 25 intersecting at its forward lower corner the upper end of the said cam-slot 18, to permit the extension into the said slot of a latching-finger 26 extending downwardly and forwardly from a pivotal action-slide latch 27 located in the said recess 25. The said latch is provided at its rear end with a pivot-stud 28 rigidly secured thereto and projecting inwardly therefrom for pivotal bearing in a bore 29 opening laterally out of the rear end of the recess 25.

Adjacent its forward end, the action-slide latch 27 is formed with an inclined cam-slot 30 flared or widened toward its lower end and having an inclined lifting cam-surface 31 and an inclined depressing cam-surface 31a. The said cam-slot

30 receives an operating-pin 32 rigidly mounted in and laterally offsetting from a reciprocating firing-pin 33 and projecting through a longitudinal guide-slot 34 in the side wall of the breech-bolt 19, as clearly shown in Figs. 5 and 6. The said firing-pin is arranged substantially longitudinally of the arm and reciprocates in a bore 35 formed in the breech-bolt 19 and opening through the rear end thereof to permit the projection of the rear end of the firing-pin therefrom. The forward end of the bore 35 has a contracted portion 36, as shown in Fig. 5, through which the firing-point 37 formed upon the forward end of the firing-pin 33 projects for engagement with a cartridge, in the usual manner of bolt-action firearms.

At its rear end the bore 35 in the breech-bolt 19 is provided with an enlarged portion 38 in which bears the enlarged rear end 39 of the firing-pin 33 and which results in the formation of a rearwardly-facing shoulder 40 engaged by the forward end of a helical retracting-spring 41 encircling a portion of the said firing-pin and bearing at its rear end against the forwardly-facing shoulder 42 formed at the junction between the firing-pin 33 proper and its enlarged portion 39. The said spring 41 serves, on occasion, to move the firing-pin 33 rearwardly so as to engage its laterally projecting operating-pin 32 with the lower portion of the depressing cam-surface 31^a of the cam-slot 30 in the action-slide latch 27.

When the firing-pin 33 is in its rearmost position, its rear end projects from the rear end of the bore 35 in the bolt 19 in position to be struck by a hammer 43 of usual form and requiring no detailed description herein other than to say that it is released (for firing) in the usual manner by a trigger 44.

The latching-finger 26 which forwardly and downwardly offsets from the action-slide latch 27 is adapted to engage, on occasion, with a rearwardly-facing latching-abutment 45 forming a feature of the bolt-operating lug 17 of the action-slide bar 15, and formed by notching the said lug 45 as at 46.

At its forward end the breech-bolt 19 is formed with a pair of locking-lugs 47 and 48 (Figs. 5 and 6) respectively offset therefrom in opposite directions and entering suitable notches 49 and 50 formed in the upper portion of the side walls of the receiver 10. The entry of the locking-lugs 47 and 48 of the breech-bolt into the notches 49 and 50 respectively takes place when the said breech-bolt is moved into its closed position and serve to prevent the said breech-bolt from moving rearwardly as the result of the firing of the cartridge.

For convenience of description, let it be presumed that the action-slide bar 15 has been manually moved by means of its handle 14 to the limit of its forward movement after the hammer 43 has been cocked by a previous rearward travel of the breech-bolt 19. With the parts in the positions referred to, the bolt-operating lug 17 of the action-slide bar 15 will be located in the forward upper portion of the cam-slot 18 in engagement with the depressing cam-surface 22. The firing-pin 33 will, under these circumstances, have been retired to the limit of its rearward movement by the spring 41 and will have acted through the intermediary of its operating-pin 32 and the depressing cam-surface 31^a to swing the action-slide latch 27 downwardly to interpose the latching-finger 26 thereof in the path of the rearward travel of the latching-abutment 45 on

the bolt-operating lug 17 so that the action-slide bar 15 will thus be prevented, for the time being, from being moved rearwardly, as for instance by an inadvertent rearward pull upon the handle 14.

If, now, the trigger 44 is pulled to permit the hammer 43 to drive the firing-pin forwardly for firing a cartridge, in which position it is shown in Fig. 2, the action slide latch 27 will be swung upwardly by the forward firing motion of the firing-pin as just referred to, with the effect of 10 engaging the pin 32 with the lifting cam-surface 31 to thus lift the latching-finger 26 out of the path of the latching-abutment 45 and thereby release the action-slide bar 15 for rearward travel. It will be noted that the unlatching of the action-slide bar 15 as just described is completed only 15 when the firing-pin 33 is substantially at the limit of its forward travel and is not dependent upon some action antecedent to the firing movement of the said firing-pin, so that if, when the gun is fired, the user is pressing rearwardly upon the action-slide handle 14, the said action-slide bar 15 will not be released for moving the breech-bolt from its fully-closed position until the cartridge has actually been fired. 20 25

After the action-slide bar 15 has been unlatched as above described, the manual rearward movement thereof will disengage the now-unlatched bolt-operating lug 17 from the depressing cam-surface 22 of the cam-slot 18 in the breech-bolt 19 and after a limited amount of free travel or lost motion will engage the said lug with the lifting cam-surface 20. The further rearward travel of the action-slide bar 15 will cause the said lug 17 (acting upon the lifting cam-surface 20) to swing the forward end of the bolt 19 upwardly and when the said lug becomes engaged with the curved reach 23 of the slot 18, the locking-lugs 47 and 48 of the bolt 19 will have been lifted clear of the locking-notches 49 and 50 and the said breech-bolt 19 will be moved rearwardly by the lug 17 into the position in which it is shown by broken lines in Fig. 3.

The rearward travel of the breech-bolt 19, as just above described, serves to cock the hammer 43 and thus permits the spring 41 to move the firing-pin rearwardly with the effect of engaging the operating-pin 32 with the depressing cam-surface 31^a of the latch 27 to swing the forward end of the said latch downwardly. The forceful depression of the latch 27 as just described will take place only in the event that the same has not previously fallen by gravity during the rearward travel of the firing-pin with respect to the breech-bolt. 55

With the breech-bolt in its fully-retired position and the hammer 43 cocked as above described, a new cartridge may be inserted into the barrel 12; then, when the action-slide bar 15 is moved forwardly by the user of the arm, the bolt-operating lug 17 will be thereby caused to exert a concurrent effort to move the breech-bolt 19 bodily forwardly and swing the forward end of the same downwardly, but inasmuch as the locking-lugs 47 and 48 are at this time riding upon the upper edges of the respective side walls of the receiver, no other than a forward movement of the bolt can result until such time as the said lugs are brought into registration with the locking notches 49 and 50. 60 65 70

When the lugs 47 and 48 have been brought fully into registration with their respective notches 49 and 50, the continued forward movement of the action slide will depress the forward end of the said breech-bolt to seat the lugs 47 75

and 48 in their respective locking-notches 49 and 50. Shortly before the action-slide bar 15 reaches the limit of its forward movement, the bolt-operating lug 17 thereof will have engaged the under side of the latching-finger 26 which is being at this time bodily depressed with the bolt. The said lug will momentarily swing the latch 27 upwardly with respect to the bolt, with the effect of slightly moving the firing-pin 33 forwardly, 10 but when the latch-abutment 45 has advanced into registration with the forward face of the latching-finger 26, the latch will be immediately swung downwardly by the urge of the spring 41 acting through the firing-pin 33, operating-pin 15 32 and depressing cam-surface 31a.

The parts will now have been restored to the positions in which they are shown in Fig. 4, preparatory to another cycle of operations.

In the event that it is desired, for any reason, 20 to open the breech of the gun without causing the hammer 43 to strike the firing-pin 33 in the usual manner, the said firing-pin may be manually moved against the tension of the spring 41, by pressing with the finger upon its rear end, to thus 25 forcibly lift the latching-finger 26 of the action-slide latch 27 out of the path of the latching-abutment 45, as before described.

In the construction herein shown and described, 30 the latch 27 is positively moved into both its unlatching and latching positions by the operating-pin 32 on the firing-pin 33. Thus, the movement of the said latch as above referred to may be said to occur concurrently with the movement of the firing-pin, despite the limited free movement of the 35 operating-pin 32 in the slot 30 of the said latch.

The invention may be carried out in other specific ways than that herein set forth without departing from the spirit and essential characteristics of the invention, and the present embodiment is therefore to be considered in all respects as illustrative and not restrictive, and all changes coming within the meaning and equivalency range 45 of the appended claims are intended to be embraced therein.

I claim:

1. In a bolt-action firearm, the combination with a retractable breech-bolt; of a reciprocating firing-pin carried by the said breech-bolt and having a laterally-offsetting operating-projection; a manually-reciprocatable action-slide having lost-motion connection to the said breech-bolt for operating the same; and a latch-member 50 acting to releasably check the rearward movement of the said action-slide with respect to the said breech-bolt and provided with a cam-surface engaged by the laterally-offsetting operating-projection of the said firing-pin for being positively and concurrently moved into its unlatching position by the said firing-pin during the firing movement thereof.

2. In a bolt-action firearm, the combination with a retractable breech-bolt; of a reciprocating firing-pin carried by the said breech-bolt and having a laterally-offsetting operating-projection; a manually-reciprocatable action-slide having lost-motion connection to the said breech-bolt for operating the same; and a latch-member 55 carried by the said breech-bolt and acting to releasably check the rearward movement of the said action-slide with respect to the said breech-bolt and provided with a cam-surface engaged by the laterally-offsetting operating-projection 60 of the said firing-pin for being moved into its

unlatching position by the firing movement of the said firing-pin.

3. In a bolt-action firearm, the combination with a retractable breech-bolt; of a reciprocating firing-pin carried by the said breech-bolt and 5 having a laterally-protruding operating-projection; a manually-reciprocatable action-slide having lost-motion connection to the said breech-bolt for operating the same; and a pivotal latch-member carried by the said breech-bolt and acting to releasably check the rearward movement of the said action-slide with respect to the said breech-bolt and provided with a cam-surface 10 engaged by the laterally-protruding operating-projection of the said firing-pin for being turned 15 into its unlatching position by the firing movement of the said firing-pin.

4. In a bolt-action firearm, the combination with a movable breech-bolt; of a firing-member, 20 a manual operating-member operatively connected to the said breech-bolt for operating the same; a latch-member for releasably checking the breech-opening movement of the said operating-member; and double-acting actuating-means, including a latch-actuating abutment 25 rigidly carried by the said firing-pin, operatively interconnecting the said firing-member and the said latch-member, the said double-acting actuating-means serving to cause the positive movement of the said latch-member into its unlatching 30 position in response to and concurrently with the firing movement of the said firing-member, and to cause the positive movement of the said latch-member into its latching position in response to and concurrently with the retiring 35 movement of the said firing-member.

5. In a bolt-action firearm, the combination with a movable breech-bolt; of a reciprocating firing-pin carried by the said breech-bolt; a manual operating-member connected to said 40 breech-bolt for operating the same and having movement with respect thereto; a latch-member acting to releasably check the movement of the said operating-member; and actuating-means, including a latch-actuating abutment rigidly carried by said firing-pin, serving to operatively connect the said latch-member to the said firing-pin in such manner as to cause the firing movement of the said firing-pin to positively and concurrently move the said latch-member into its 45 unlatching position.

6. In a bolt-action firearm, the combination with a movable breech-bolt; of a reciprocating firing-pin carried by the said breech-bolt; a manual operating-member connected to said 50 breech-bolt for operating the same and having movement with respect thereto; a latch-member carried by the said breech-bolt and acting to releasably check the movement of the said operating-member; and actuating-means, including a latch-actuating abutment rigidly carried by the said firing-pin, serving to operatively connect the said latch-member to the said firing-pin in such manner as to cause the firing movement of the said firing-pin to positively and concurrently 55 move the said latch-member into its unlatching position.

7. In a bolt-action firearm, the combination with a movable breech-bolt; of a reciprocating firing-pin carried by the said breech-bolt; a manual operating-member connected to said 60 breech-bolt for operating the same and having movement with respect thereto; a latch-member acting to releasably check the movement of the said operating-member; spring-means urging the 65

said firing-pin into its retired position; and actuating-means, including a latch-actuating abutment rigidly carried by the said firing-pin, serving to operatively interconnect the said latch-member and the said firing-pin in such manner as to cause the firing movement of the said firing-member to positively and concurrently move the said latch-member into its unlatching position and to cause the retiring movement of the 10 said firing-pin under the urge of the said spring-means to cause the movement of the said latch-member into its latching position.

8. In a bolt-action firearm, the combination with a retractable breech-bolt; of a reciprocating 15 firing-pin carried by the said breech-bolt; a manually reciprocatable action-slide connected to said breech-bolt for operating the same and having movement with respect thereto; a latch-member acting to releasably check the movement of the said action-slide; spring-means urging the said firing-pin into its retired position; and actuating-means, including a latch-actuating 20 abutment rigidly carried by the said firing-pin, serving to operatively interconnect the said latch-member and the said firing-pin in such manner as to cause the firing movement of the 25 said firing-pin under the urge of the said spring-means to cause the movement of the said latch-member into its unlatching position.

9. In a bolt-action firearm, the combination with a retractable breech-bolt; of a reciprocating 30 firing-pin carried by the said breech-bolt; a hammer for driving the said firing-pin into its firing position; a manually-reciprocating action-slide connected to the said breech-bolt for operating the same and having movement with respect thereto; a latch-member acting to releasably check the movement of the said action-slide; and actuating-means including a latch-actuating abutment rigidly carried by the said firing-pin serving to operatively connect said 35 latch-member to the said firing-pin in such manner as to cause the said firing-pin when struck by the said hammer to positively and concurrently move the said latch-member into its unlatching position.

50 10. In a bolt-action firearm, the combination with a retractable breech-bolt; of a reciprocating firing-pin carried by the said breech-bolt; a hammer for driving the said firing-pin into its firing position; a manually reciprocatable action-slide connected to the said breech-bolt for operating the same and having movement with respect thereto; a latch-member acting to releasably check the movement of the said action-slide; spring-means urging the said firing-pin into its retired position; and actuating-means, including a latch-actuating abutment rigidly carried by the said firing-pin operatively interconnecting the said latch-member to said firing-pin in such manner as to cause the movement 55 of the said firing-pin under the urge of the said hammer to effect the positive and con-

current movement of the said latching-member into its unlatching position and to cause the retiring movement of the said firing-pin under the urge of the said spring-means to effect the movement of the said latch-member into its latching 5 position.

11. In a bolt-action firearm, the combination with a retractable breech-bolt; of a reciprocating firing-pin carried by the said breech-bolt; a manual operating-member having lost-motion 10 connection to the said breech-bolt for operating the same; a latch-member acting to releasably check the movement of the said operating-member in the direction for taking up the lost motion of the connection between the same and the 15 said breech-bolt; and actuating-means including a latch-actuating abutment rigidly carried by the said firing-pin, serving to operatively connect the said latch-member to the said firing-pin in such manner as to cause the firing movement 20 of the said firing-pin to positively and concurrently move the said latch-member into its unlatching position.

12. In a bolt-action firearm, the combination with a retractable breech-bolt; of a reciprocating 25 firing-pin carried by the said breech-bolt; a hammer for driving the said firing-pin into its firing position; a manually-reciprocatable action-slide having lost-motion connection to the said breech-bolt for operating the same; a latch-member acting to releasably check the movement of the said action-slide in the direction for taking up the lost motion of the connection between the same and the said breech-bolt; and actuating-means, including a latch-actuating abutment 30 rigidly carried by the said firing-pin, serving to operatively connect said latch-member to the said firing-pin in such manner as to cause the said firing-pin when struck by the said hammer to positively and concurrently move the said 35 latch-member into its unlatching position.

13. In a bolt-action firearm, the combination with a retractable breech-bolt; of a reciprocating firing-pin carried by the said breech-bolt; a hammer for driving the said firing-pin into its 40 firing position; a manually-reciprocatable action-slide having lost-motion connection to the said breech-bolt for operating the same; a latch-member acting to releasably check the movement of the said action-slide in the direction for taking up the lost motion of the connection between the same and the said breech-bolt; spring-means urging the said firing-pin into its retired position; and actuating-means including a latch-actuating abutment rigidly carried by the said firing-pin, operatively interconnecting the said latch-member to said firing-pin in such manner as to cause the movement of the said firing-pin under the urge of the said hammer to effect the positive and concurrent movement of the said 45 latching-member into its unlatching position and to cause the retiring movement of the said firing-pin under the urge of the said spring-means to effect the movement of the said latch-member into its latching position.

FRANK F. BURTON.
